Attorney

UNITED STATES PATENT OFFICE.

JEFFERSON PAUL JONES, OF JONESVILLE, MICHIGAN.

WHIFFLETREE.

1,087,661.

Specification of Letters Patent.

Patented Feb. 17, 1914.

Application filed May 7, 1913. Serial No. 766,121.

To all whom it may concern:

Be it known that I, JEFFERSON PAUL JONES, a citizen of the United States, residing at Jonesville, in the county of Hillsdale and State of Michigan, have invented certain new and useful Improvements in Whiffletrees, of which the following is a specification, reference being had to the accompanying drawings.

10 This invention relates to new and useful improvements in whiffletrees, and more particularly to a combined double tree and swingletree, the object of the invention being to provide a whiffletree which can be 15 quickly converted into either a doubletree or a swingletree.

Another object of the invention is to provide a whiffletree of the above character which will possess advantages in points of 20 efficiency and durability, is inexpensive to manufacture, and at the same time is simple in construction and operation.

With these and other objects in view, my 25 invention consists in the novel features of construction, combination and arrangement of parts, as will be hereinafter more fully described, claimed, and pointed out in the accompanying drawings, in which

Figure 1 is a top plan view illustrating 30 the application of my invention. Fig. 2 is an elevation of the locking plate. Fig. 3 is an end view of the locking plate. Fig. 4 is a horizontal sectional view of the whiffletree holder and locking plate, and Fig. 5 is 35 an elevation of the locking plate illustrating a modified form thereof.

Referring more particularly to the drawings, 1 indicates a doubletree, the intermediate portion of which is provided with the 40 usual clevis 2, whereby the same may be readily secured to a plow or other implement. The doubletree is further provided at each end thereof with a pair of spaced parallel openings 3. Slidably mounted upon 45 the rear face of the doubletree and arranged at each end thereof, is a plate 4, said plate being provided adjacent each end thereof with the open-ended slots 5 and further provided at its ends with the elongated slots 6 which are adapted to receive the guide pins 7 carried by the doubletree 1. The intermediate portion of the plate 4 is provided with an arcuate raised portion 8, which is adapted to be engaged by the fingers or a 50 suitable tool, to actuate the plate 4.

A U-shaped connecting member 9 is pro-

vided, the ends of which are further provided with the notches 10, which are adapted to receive the side edges of the open-ended slots 5 after they have been passed through the openings 3. From this, it will be readily apparent that in order to secure the U-shaped member 9 to the ends of the doubletree, the plate 4 is raised so that the ends of the member 9 may be readily inserted through the openings 3. The plate is then pressed downwardly so that the side walls of the open-ended slots 5 will engage within the notches 10 formed in the ends of the member 9. From the description, it will be readily apparent that by the position of the plate, it will be readily held into engagement with the ends of the member 9 to prevent the withdrawal of the same until the plate has been raised sufficient so that 75 the side walls of the open-ended slots 5 are entirely removed from the notches 10.

From the above, it will be readily apparent that the swingletree 11 may be quickly and readily attached to the ends of 80 the doubletree or easily removed therefrom. In the construction of the whiffletree, I provide that form of trace hook which consists of a circular body member 12 adapted for engagement over the ends of the swingletree and which is held thereon by means of the spring plate 13, the inner end of said plate being secured to the swingletree, as shown at 14, and said plate being further secured to the body 12 of the trace hook, as 90 shown at 15. The outer end of the plate 13 projects beyond the body 12 and is provided with an opening 16 which is adapted to receive the inner reduced end 17 of a spring actuated plate 18.

In Fig. 5 I have illustrated a modified form of plate which is adapted for application to both ends of the doubletree 1. This form of plate is preferably constructed of a single length of wire, the intermediate portion of which is bent upon itself to form the spaced open-ended loops 16', which are adapted for engagement with the ends of the U-shaped member 9 to securely hold the same in its operative position. The ends of 100 the wire are bent to provide elongated loops 17' which are slidably mounted upon the guide pins 7. It will be readily apparent that this form of device may be readily exchanged for the plate illustrated in Fig. 2. 110

From the above description taken in connection with the accompanying drawings,

it will be apparent that I have provided a simple and durable whiffletree which can be quickly and readily converted from a doubletree to a swingletree, or vice versa. It 5 will be apparent that my device is extremely simple in construction and can be manufactured at a comparatively low cost.

While I have shown and described the preferred form of my invention, it will be 10 obvious that various changes in the details of construction and in the proportions may be resorted to for successfully carrying my invention into practice without sacrificing any of the novel features of departing from 15 the scope of the appended claims.

What I claim:

1. In combination with a doubletree provided at each end with a pair of spaced parallel openings, of a plate slidably mounted 20 upon the ends of the doubletree, said plate being provided with spaced open-ended slots, and a U-shaped member having its ends adapted for insertion through said openings and provided with oppositely disposed notches adapted to receive the side walls of the open-ended slots of the plate.

2. In combination with a doubletree having a pair of spaced parallel openings at each end thereof, of a sliding plate mounted 30 upon the ends of the doubletree, and a U-shaped member having its ends adapted for insertion through said openings and provided with oppositely disposed notches to receive portions of said plate to securely 35 retain the ends of said member within the openings.

3. In combination with a doubletree having a pair of spaced parallel openings at each end thereof, of a plate slidably mounted 40 upon the ends of said doubletree and having open-ended slots adjacent each end thereof, said plate being provided with elong-

gated slots, guide pins carried by the doubletree and arranged within said elongated slots, and a U-shaped member having its 45 ends adapted for insertion through the openings in the doubletree and further provided with oppositely disposed notches adapted to receive the side walls of the open-ended slots of the plate to removably secure the 50 ends of said member within the openings.

4. In combination with a doubletree having a pair of spaced parallel openings at each end thereof, of a U-shaped member having its ends adapted for insertion through 55 said openings, and provided with oppositely disposed notches, and means slidably mounted upon the ends of said doubletree and adapted for engagement with the ends of the U-shaped member to removably secure 60 the same within the openings.

5. In combination with a doubletree having a pair of spaced parallel openings at each end thereof, of a sliding plate comprising a single length of wire having its intermediate portion bent upon itself to form a pair of spaced open-ended loops and the ends bent to form elongated loops, guide pins carried by the ends of the doubletree and arranged within said elongated loops, and a 70 U-shaped member having its ends adapted for insertion through said openings and provided with oppositely disposed notches adapted to receive the side walls of the open-ended loops to removably secure the ends 75 of said U-shaped member within the open ends.

In testimony whereof I hereunto affix my signature in the presence of two witnesses.

JEFFERSON PAUL JONES.
